ONE-HALF TO ALBERT ERNEST BABKIRK, OF WOODSTOCK, NEW BRUNSWICK,
CANADA.

REVERSIBLE TURBINE.

1,300,889.

Specification of Letters Patent. Patented Apr. 15, 1919.

Application filed May 2, 1918. Serial No. 232,094.

To all whom it may concern:

Be it known that I, ALFRED J. SPARROW, a subject of the King of Great Britain, residing at Woodstock, in the Province of New 5 Brunswick and Dominion of Canada, have invented certain new and useful Improvements in Reversible Turbines; and I do hereby declare the following to be a full, clear, and exact description of the invention, such as will enable others skilled in the 10 art to which it appertains to make and use the same.

The present invention comprehends generally improvements in steam engines and 15 more particularly to a rotary engine.

It is the principal aim and object of this invention to provide a device of the above mentioned character wherein valve means of a novel construction are arranged for 20 conducting and exhausting steam to and from the stator for the effective operation of the rotor therein.

It is an equally important object of this invention to provide a device of the above 25 mentioned character wherein manually controlled valve means of a novel construction are employed for coöperating with the valve means which controls the admission and exhausting of steam to the stator so as to shift 30 the last mentioned valve means and permit of the reversing of the operation of the engine when desired.

More particularly the present invention embraces the provision of a motor of the 35 above mentioned character embodying a stator in which is operably mounted a rotor, the normally extensible pistons of which are designed to receive the impact produced by the admission of steam into the stator for 40 the rotation of the stator while coöperating with these pistons are improved means integral with the inner surface of the stator for successively retracting the pistons preparatory to the admission of steam into the 45 adjacent compartments provided in the stator by the pistons, consequently insuring an effective operation of the engine.

More specific objects of this invention consists in the provision of the means for 50 manually controlling the position of the reversing valve; and to provide improved packing means for preventing the escape of steam during the actuation of the engine.

Among the other aims and objects of this 55 invention may be recited the provision of a

rotary engine of the character described with a view to compactness, and in which the number of parts are few, the construction simple and the cost of production low and the efficiency high.

Other improvements and novel details in the construction and arrangement of the various parts of the apparatus will be brought out more in detail in the description to follow, which for a clear understanding 60 of the invention should be considered in connection with the accompanying drawings forming a part hereof, and wherein is disclosed for the purpose of illustration a convenient and satisfactory embodiment of 65 the invention. It is to be noted in this connection that minor changes may be made without departing from the principle of operation of the various parts.

The invention is clearly illustrated in the 75 accompanying drawings, in which:—

Figure 1 is an elevation of the improved turbine,

Fig. 2 is a vertical longitudinal section of the invention, the valves being shown in 80 one position,

Fig. 3 is a vertical transverse section thereof,

Fig. 4 is a fragmentary vertical longitudinal sectional detail showing the valve means 85 shifted, and

Fig. 5 is a vertical transverse section through a sliding valve operating means embodied in the invention.

Similar characters of reference are employed in all of the above described views, to indicate corresponding parts.

Referring now, more particularly, to the accompanying drawings there is provided a base 1 from which projects standards 2 95 provided at their upper ends with bearings 3 while carried within the space between the standards is a stator 4. This stator consists of a cylindrical casing 5 having an open side normally closed by a cover plate 100 6 held in position by means of suitable fasteners such as screws 7. The inner surface of the casing near the upper edge thereof is provided with an enlargement 8 for a purpose that will presently appear. A 105 shaft 9 is journaled through centrally arranged bearing openings 10 while the ends thereof are journaled in the bearings 3 formed at the upper ends of the standards. A rotor indicated in its entirety by the 110

- numeral 11 is rigidly connected to the shaft, preferably through the instrumentality of a key 12, and is positioned within the casing, the uppermost point on the outer surface thereof being arranged in close relation with the enlargement 8, as indicated in Figs. 2 and 4, for a purpose that will presently appear. The rotor preferably consists of a disk-like body which is arranged in uniformly spaced relation with the inner surface of the casing with the exception of the uppermost portion which engages the enlargement as intimated, and is provided with a plurality of radially arranged and uniformly spaced slots 13 which open in the outer periphery and accommodate sliding pistons 14, the latter being normally held extended and in yielding engagement with the inner surface of the casing through the instrumentality of suitable resilient means such as coiled springs 15. By the peculiar construction and arrangement of these pistons it will be apparent that they will be successively retracted upon engagement with the enlargement so as to insure of the directing of the intake against the adjacent piston. Incidentally it will be noticed that these pistons coöperate with the casing in providing compartments.
- As intimated, improved means has been provided for controlling the admission and exhaustion of steam to and from the stator for the rotation of the rotor therein.
- In reducing this feature of the invention to practice, the upper portion of the casing is provided near the respective ends of the enlargement with openings 16 and 17 which serve as inlet and exhaust passages. Connected in these openings are nipples 18, the upper ends of which are connected to the bottom and near the respective ends of a valve casing 19. This valve casing is preferably of a rectangular configuration and is provided with openings 20 in the top at points opposite the nipples 18 for receiving the branches 21 and 22 of the steam or other supply pipe 23. An exhaust pipe 24 is led centrally from the top of the casing 19 and between the openings 20 as indicated in the drawings. Coöoperating with the branches and nipples is an improved valve body indicated in its entirety by the numeral 24'. The body is preferably of a rectangular configuration and is slidable in the casing having the outer surfaces thereof arranged in close relation with the inner surfaces of the casing. The valve body 24' is provided near its ends with vertical passages 25 and 26, either of which may be arranged to establish communication between either of the opposed inlet branches and nipples so that steam may enter the stator casing and strike the blades or pistons 14 for rotating the rotor within the stator, as is apparent.
- The valve body 24' is further provided with

an inverted U-shaped passage 27, the vertical end portions 28 of which are positioned so that either one of them will establish communication with the nipple which is not arranged in communication with one of the inlet branches so that exhaust steam may pass from the compartment within the stator and through the opening 29 which establishes communication with the exhaust pipe 24, as is apparent.

With a view toward providing means for shifting the valve body 24' so as to reverse the operation of the engine when desired, there is employed a piston casing or cylinder 30 which is detachably connected as at 31 to the open end of the valve casing 19. The outer end of this casing 30 is closed by a detachable cover plate 32 which permits of access to the casing when desired. A piston head 33 operates in the casing 30 and is connected to one end of a piston rod 34, the opposite end of which is connected as at 35 to the adjacent end of the valve body 24' so that upon the shifting of the piston head 33 the valve body 24' will be correspondingly shifted so that the parts may be arranged in the position indicated in Fig. 4 for the purpose of reversing the operation of the engine. The casing 30 is provided with a steam conducting passage 36 which communicates with opposite ends of the casing while a conducting pipe 37 is led from one of the branches 22 and communicates with the passage 36 medially of the ends thereof. A valve seat 38 is formed transversely of the passage way 36 near the point of communication of the pipe 37. A valve plug 39 is arranged in the seat 38. A handle 40 is connected with the valve 39 for turning the valve plug for alining an angular passage way 41 of the same with either portion of the passage way 36 and with the pipe 37 allowing steam to flow through the pipe 37 and at one end of the passage way 36 into the adjacent ends of the casing 30 for shifting or moving the piston heads 33 to consequently move or shift the valve body 24' in a corresponding direction.

To prevent the escape of steam from the compartments in the stator between the adjacent and closely arranged side edges of the stator and the rotor, the inner surfaces of the sides of the casing 5 and the cover plate 6 are provided at points near the bearing openings 10 and near the inner surfaces of the walls of the casing with opposed grooves 42 for receiving packing rings 43, the outer edges of which are arranged in close relation with the adjacent side edges of the rotor, as indicated in Fig. 3.

The mode of operation of the present invention may be reviewed as follows:

Assuming that the parts have been assembled in the manner described and as indicated in the drawings, especially in Fig. 2,

steam passes from the supply pipe 23 through the branch pipe 21 thereof and thence through the vertical passage way 25 in the valve body 24', through the alining 5 nipple 18 and passage way 16 into the adjacent compartment of the stator while this steam will strike the adjacent piston 14 which impact causes a rotation of the rotor. As long as the parts remain in this position, the 10 rotor will be rotated by the steam successively striking the pistons. In this connection it is to be noted that the exhaust steam passes through the passage way 17, the nipple therein, and thence through the vertical 15 portion 28 which alines with the nipple into the U-shaped passage way and finally passes through the opening 29 into the exhaust pipe 24. Particular attention is directed to the fact that just before the pistons 14 are disposed so as to receive the impact from the 20 intake they are engaged and retracted by the enlargements, this arrangement insuring of the steam being directed against the piston which is opposed to the intake passage way 25 16, as indicated in Fig. 2. To reverse the operation of the turbine, the handle 40 is engaged so that steam will pass through the pipe 37 from the branch 22 by the valve plug and through one end of the passage way 36 30 so as to enter the casing and act against the piston head 33 so as to shift this head as well as the valve body 34 to the position as indicated in Fig. 4, the valve body 24 closing the branch pipe 21 and stopping so that 35 the passage way 26 establishes communication between the branch pipe 22 and the nipple which is mounted in the opening 17, permitting of steam to strike the opposite sides of the piston for the rotation of the 40 rotor in an opposite direction while the exhaust steam of course passes through the nipple 18 in the passage way 16 into the adjacent vertical portion 28 of the U-shaped passage way 27 and finally passes through 45 the opening 29 into the exhaust pipe 24.

It is believed in view of the foregoing description that a further detailed description of the operation of the invention is unnecessary. Likewise, it is believed that the advantages of the invention will be readily apparent.

As many changes could be made in the above construction and many apparently widely different embodiments of this invention could be made without departing from the scope thereof it is intended that all matter contained in the above description or shown in the accompanying drawings shall be interpreted as illustrative and not in a limited sense. It is also to be understood that the language used in the following claims is intended to cover all the generic and specific features of the invention herein

described and all statements of the scope of the invention which as a matter of language 65 might be said to fall therebetween.

Having thus fully described the invention, what is claimed as new and desired to be secured by Letters Patent is:

1. A device of the character described including a stator, a rotor therein, nipples mounted through the upper edge of the stator near opposite sides thereof and serving as inlet and exhaust passages, a valve casing having connection with the nipples, a steam supply pipe having its branches communicating with the top of the casing at points opposite the nipples, an exhaust pipe leading from the top of the casing, a valve body 70 75 80 85 90 95 100 105 110 115 120 body 115 120 125 130 135 140 145 150 155 160 165 170 175 180 185 190 195 200 205 210 215 220 225 230 235 240 245 250 255 260 265 270
